UNITED STATES PATENT OFFICE.

PATRICK GORMLY, OF PHILADELPHIA, PENNSYLVANIA.

AUTOMATIC AIR-VALVE FOR STEAM-RADIATORS.

SPECIFICATION forming part of Letters Patent No. 315,933, dated April 14, 1885.

Application filed October 27, 1884. (No model.)

To all whom it may concern:

Be it known that I, PATRICK GORMLY, a citizen of the United States, and a resident of Philadelphia, Pennsylvania, have invented 5 certain Improvements in Automatic Air-Valves for Steam-Radiators, of which the following is a specification.

My invention relates to automatic valves for the discharge of air from a steam-radiator on 10 first turning on the steam, and for the admission of air thereto when the steam is cut off, the objects of my improvements being to insure the quick action of the valve, and to prevent the same from being tampered with by 15 meddlesome persons.

In the accompanying drawings, Figure 1 is a longitudinal section of an automatic air-valve constructed in accordance with my invention; Fig. 2, a transverse section of the 20 same; Fig. 3, a sectional plan view on the line 1 2, Fig. 1; Fig. 4, a sectional plan view on the line 3 4, Fig. 1; and Fig. 5, a sectional view illustrating a modified form of air-valve.

In Figs. 1 to 4, A and B are two pipes or 25 tubes secured at the upper and lower ends to rings a, and inclosing an annular chamber, b, the pipe A having at the lower end a branch, d, for attachment to one of the pipes of the radiator.

Extending transversely across the tube B, 30 near the upper end of the same, is a pipe, f, communicating at each end with the chamber b, and having in the top an opening, i, Fig. 3, the edge of which forms the seat for a valve, m, the latter consisting of the conical end of 35 a set-screw, n, adapted to a nut, s, forming part of a yoke, t, which embraces the pipe f, and is secured to the upper end of a rod, w, the lower end of which is confined to a trans- 40 verse bar, x, secured to the tube b, near the lower end of the same. When the steam is cut off from the radiator, the pipes of the same and the chamber b are filled with air, and the parts are in the position shown in the drawings, the valve m being free from contact with 45 its seat. When the steam is first admitted to the radiator, it drives the air from the same, and through the branch d, chamber b, and pipe f, the air escaping through the opening 50 i; but as soon as the radiator has been filled

with steam and the latter gains access to the chamber b the tubes A and B will be expanded, thus causing the seating of the valve m, so as to prevent the escape of steam. When steam is cut off from the radiator and condensation takes place, the tubes A and B are contracted, so as to again expose the opening i for the admission of air to the radiator. The quick action of the device is insured, owing to the fact that the rod w and yoke t, forming 55 the valve-carrier, are exposed on all sides to the current of air rising through the tube B, so that there is little or no expansion of said valve-carrier when the tubes are expanded on the admission of steam to the chamber b. 60 The tubes are carried up beyond the top of the yoke t, so as to form a casing or guard which incloses the set-screw n, of which the valve forms part, thereby overcoming an objection to that class of air-valves in which the 65 valve-screw is exposed, as such exposed valves are liable to be tampered with by meddlesome persons and the proper action of the valve thereby defeated. This tubular casing also provides a support for the cover y, which is 70 preferably perforated for the escape of air.

In Fig. 5 I have shown a modification of my invention, in which the steam-chamber is within a pipe, b', having a valve-seat at the end, the valve-carrier t' being in the form of 80 a tube open at the bottom and surrounding the pipe b'. This device contains, however, the two essential features of the invention—namely, the valve-carrier exposed on all sides to the air, and the casing or guard inclosing 85 the valve-screw. Where the yoke t is employed, the rod w may be dispensed with and the legs of the yoke carried down and secured at or near the bottom of the tube B, as shown by dotted lines in Fig. 1. 90

I claim as my invention—

1. The combination of the casing containing a chamber communicating with the radiator, and having an inclosed or guarded valve-seat, a valve adapted to said seat and contained within the guard, and a valve-carrier exposed on all sides to the air, as set forth. 95

2. The combination of the tubes A and B, the branch d, the transverse tube f, with valve-seat therein, the valve m, the yoke t, carrying 100

said valve, and a support for said yoke, as set forth.

3. The combination of the tubes A and B, the branch *d*, the transverse tube *f*, with valve-
5 seat, the valve *m*, the yoke *t*, carrying the same, the rod *w*, and the cross-bar *x*, as set forth.

In testimony whereof I have signed my name to this specification in the presence of two sub-
scribing witnesses.

PATRICK GORMLY.
